THERMOELECTRIC SPACE HEATER

Frederick J. Bordt, Averill Park, N. Y., and Andrew J. Shine, Xenia, Ohio, assignors to the United States of America as represented by the Secretary of the Army

Application June 23, 1952, Serial No. 295,026

7 Claims. (Cl. 126—67)

1

Our invention relates to heaters of the type embodying a thermoelectric generator.

A primary object of the invention is to provide a space heater having air circulating means operated by a thermoelectric generator, or thermopile, forming a part of the heater.

A further object is to provide an air circulating heater which requires no external source of electrical power to operate the air circulating fans.

A further object is to provide in a heater of the above-mentioned character a novel and simplified thermoelectric generator unit which is easy to assemble, disassemble, and maintain.

A further object is to provide a thermoelectric generator comprising readily removable and replaceable panels or sections.

A further object is to provide in a heater of the above-mentioned character a base or supporting structure which houses and protects the thermoelectric generator panels and bears the weight of the entire heater assembly, in such a manner that the generator panels are subjected to very little strain.

A further object is to provide a space heater in which bulkiness and weight are reduced to a minimum.

A still further object of the invention is to provide a heater of the above-mentioned character which is highly compact and simple in construction, sturdy and durable, reliable in operation and very easy to assemble and disassemble.

Other objects and advantages of the invention will be apparent during the course of the following description.

In the accompanying drawings forming a part of this application, and in which like numerals are employed to designate like parts throughout the same,

Figure 1 is a side elevation of a heater embodying our invention,

Figure 2 is an enlarged central vertical longitudinal section through the same, part broken away,

Figure 3 is a further enlarged central vertical section through a thermoelectric generator and burner unit employed in our heater,

Figure 4 is a plan view of the unit shown in Figure 3,

Figure 5 is a horizontal cross section on line 5—5 of Figure 3, with parts omitted,

Figure 6 is a fragmentary vertical section on line 6—6 of Figure 5,

Figure 7 is a plan view of an air-circulating fan adapter, part broken away and parts omitted,

Figure 8 is a fragmentary vertical section on line 8—8 of Figure 7,

2

Figure 9 is a plan view of a heat exchanger employed in our heater,

Figure 10 is an end elevation of an air-circulating fan, parts omitted,

Figure 11 is a plan view of a center cone or flow divider employed in the heater,

Figure 12 is a plan view of a combustion chamber and burner support,

Figure 13 is a side elevation of a thermoelectric generator panel or section removed,

Figure 14 is an edge elevation of the same,

Figure 15 is a horizontal section on line 15—15 of Figure 13,

Figure 16 is a diagrammatic view showing the electrical connections between an adjacent pair of thermoelectric generator panels and the fan which they operate, and,

Figure 17 is a cross section similar to Figure 15 and illustrating a slight modification of the invention.

In the drawings, where for the purpose of illustration are shown preferred embodiments of our invention, attention is directed first to Figures 1 to 16 inclusive, wherein the numeral 20 designates generally a thermoelectric generator and burner unit, constituting a support for the remainder of the heater. The unit 20 comprises an open-type frame or support which is octagonal as shown in plan, and comprising eight equidistantly spaced legs 21, having upper and lower inclined diverging portions 22 and 23, and intermediate vertical portions 24, integral therewith. The legs 21 are rigidly connected at their lower ends and above such ends by horizontal octagonal braces 25 and 26, welded or otherwise rigidly secured thereto. An additional horizontal octagonal brace 27, L-shaped in cross section, is rigidly secured by welding or the like to the inner sides of the legs, adjacent to the lower ends of their vertical portions 24, and brace 27 also serves as a support for thermoelectric generator panels or sections to be described. A top horizontal octagonal brace 28 is welded or otherwise rigidly secured to the legs 21 at their upper ends. The support thus far described is preferably formed entirely of stainless steel, although other suitable rigid and sufficiently lightweight material may be employed, if desired.

A combustion chamber and burner support unit 29 is provided, and comprises a downwardly tapering conical sheet metal sleeve or wall 30, arranged within the lower portion of the main open support, and including a top horizontal octagonal mounting flange 31, integral therewith. The mounting flange 31 is inwardly directed, Figures 3 and 6, and welded or otherwise rigidly

secured to the bottom of the L-shaped brace 27, and the entire unit 29 is thus suspended from the brace 27. The conical sleeve 30 is lined with cast refractory material 32, as shown, and a depending vertical cylindrical burner support sleeve 33 is rigidly secured by welding or the like within the lower end of the conical sleeve 30 and extends for a substantial distance below the same, Figures 2 and 3.

An outer burner sleeve or air duct section 34 engages telescopically within the support sleeve 33, and is detachably held therein by bolts 35 or the like, with the lower end of the sleeve 34 spaced above the bottom of the support, and open for the free admission of air. A tubular, vertical wick-type burner 36 is disposed centrally within the sleeve 34, and rigidly connected therewith by horizontal radial arms or brackets 37. An open annular air passage is defined by the side wall of the burner 36 and the sleeve 34, for the free upward passage of air to support combustion. The burner 36 has its top open, and disposed near and slightly below the lower end of the refractory lined sleeve 30. The burner is filled with Fiberglas wicking 38, or the like, and the bottom of the burner is connected with a liquid fuel feed line 39, leading to a constant level float valve 40, supplied with fuel from a suitable tank, not shown, by a gravity feed line 40', Figure 2. With this arrangement, a constant fuel level is maintained in the burner 36, and the Fiberglas wick 38 remains saturated with fuel, so that it is easy to start the burner in all weather conditions.

A thermoelectric generator or thermopile 41 is housed within the main open support above the unit 29. The thermoelectric generator 41 comprises eight vertical sections or panels 42 of cast ceramic material, such as Johns-Manville lightweight "Firecrete." The panels 42 have their vertical edges beveled at 43, so that the eight panels in assembly form a continuous octagonal ceramic wall, inside of the vertical leg sections 24, Figures 3 and 5. Each panel 42 is flat and rectangular in side elevation, as shown. Each panel 42 has embedded therein near its vertical edges long vertical dowel pins 44, which project slightly beyond the upper and lower ends of the panel. When the panels 42 are placed within the main support, inwardly of the leg sections 24, the lower ends of the panels engage and rest upon the L-shaped octagonal brace 27, and this brace is provided adjacent to its eight corners with pairs of openings 45, Figure 6, receiving the lower ends of the dowel pins 44. This arrangement firmly anchors the lower ends of the panels 42 to the supporting brace 27, and maintains the panels spaced slightly inwardly of the vertical leg portions 24. The panels 42 extend vertically throughout substantially the entire lengths of the leg sections 24.

An upper removable octagonal ring 46, L-shaped in cross-section, rests upon the upper ends of the panels 42 and is disposed inwardly of the leg sections 24. The removable ring 46 is arranged in opposition to the ring or brace 27, as shown, and is likewise provided near its eight corners with pairs of openings 47 which receive the upper ends of the vertical dowel pins 44, for further rigidly securing the panels in place within the main support. It will be noted that the arrangement just described renders the individual panels 42 readily removable from the generator and burner unit 20, and any one of the panels may be readily removed for servicing

or replacement, with a minimum amount of labor. In order to cushion the ceramic panels 42 against vibration and stresses from the parts of the heater whose weight they must carry, a continuous rope or pad 48 of Fiberglas wicking or the like is preferably introduced between the tops of the panels 42 and the removable ring 46, Figure 6.

Each generator panel 42 has embedded or cast therein a plurality of thermocouples 49, preferably 300 in number, and arranged in 25 horizontal rows 50, with 12 thermocouples to each row, Figure 13. Each thermocouple 49 comprises a section 51 of constantan wire, preferably 20-gage wire, approximately $\frac{3}{4}$ of an inch long; and a section 52 of 20-gage Chromel wire, approximately $\frac{3}{4}$ of an inch long. The constantan and Chromel elements 51 and 52 have their ends welded together for forming hot junctions 53, embedded within the panels 42 near the centers of the same. Cold junctions 54 of the thermocouples 49 are spaced beyond the outer faces of the ceramic panels 42, as best shown in Figure 15. Heat conducting rods or fins 55 of stainless steel or the like are welded to the hot junctions 53, and project beyond the inner faces of the panels 42. The stainless steel rods 55 are preferably about one-half inch long. Rods or fins 56 of copper or the like are welded to the cold junctions 54 of the thermocouples, and project outwardly of the panels 42, as shown. The copper rods 56 are preferably about one and one-half inches long, and the panels 42 are preferably about one-half inch thick, although these dimensions may be varied somewhat as desired. The purpose of the stainless steel rods 55 is to conduct heat rapidly to the hot junctions 53 of the thermocouples, and the copper rods 56 conduct the heat away from the cold junctions 54 and radiate heat to the air, exteriorly of the heater. This arrangement increases the temperature differential between the hot and cold junctions 53 and 54, and renders the thermocouples more efficient in the generation of electric current. It is to be noted that the hot junctions 53, embedded within the ceramic panel 42 are not exposed to oxidation, as would be the case if the hot junctions were disposed beyond the inner side of the panel 42, for direct contact with the hot combustion products. With the arrangement described above, it is only the stainless steel elements 55 which are directly contacted by the hot combustion products. The exposed cold junctions 54 are subjected to no substantial oxidizing effect, and the copper elements 56 aid in cooling the same. The thermocouples 49 of each row 50 are electrically connected in series, Figure 15, and the several rows 50 of each panel 42 are connected in series by conductors 57, welded to the endmost copper rods 56 of the rows of thermocouples, as shown. The arrangement is such that the successive rows 50 of thermocouples are connected in series in the zig-zag manner shown in Figure 13.

A center cone or flow divider 58 is disposed centrally of the panels 42 and spaced inwardly thereof and extends for the entire vertical lengths of the panels 42, Figure 3. The flow divider 58 forms with the eight panels 42 a substantially annular vertical combustion passage 59 for the upward flow of the hot gaseous combustion products generated by the burner 36. The flow divider 58 has a bottom conical extension 60, integral therewith and projecting into the combustion chamber defined by the refrac-

refractory lined sleeve 30, Figure 3. A flame baffle or spreader 61 is rigidly secured to the lower end of the extension 60 and spaced above the open top of the burner 36. The flame spreader 61 causes the flames and hot gaseous combustion products to pass upwardly between the refractory lined sleeve 30 and flow divider 58, and increases the turbulence of the upwardly flowing combustion products and flame. Above the tops of the panels 42, the flow divider 58 has a somewhat enlarged top section or sleeve 62, integral therewith, and having its open top end terminating at the top of the main support including the brace 28. The center cone or flow divider 58 is rigidly connected with an outer cylindrical adapter sleeve 63, by means of horizontal radial arms 64, Figure 11. A horizontal octagonal flange 65 is rigidly secured to the lower end of the adapter sleeve 63, and rests upon the top of the removable ring 46, Figure 6. The octagonal flange 65 may also have openings formed therein to receive the tops of the dowel pins 44, as shown in Figure 6. The top of the adapter sleeve 63 terminates a substantial distance below the top of the extension 62, and the adapter sleeve 63 is spaced radially outwardly of the extension 62 for forming a continuing annular passage for the upwardly flowing hot combustion products. It may be here noted by way of concluding the description of the thermoelectric generator and burner unit 20, that the stainless steel rods 55 project radially into the annular combustion space 59, and the copper rods 56 extend radially outwardly beyond the vertical leg sections 24, so as to be exposed to the cold air.

A lower heat exchanger and fan adapter 66 is provided, and comprises a central vertical tubular body portion 67 of sheet metal, having a bottom reduced cylindrical extension 68 which telescopes over the adapter sleeve 63. At its top end, the body portion 67 has a reduced cylindrical extension 69 for connection with a heat exchanger to be described. The tubular body portion 67 receives directly the upwardly flowing hot products of combustion from the adapter sleeve 63, and is in direct communication with the annular combustion space 59. The adapter 66 further comprises an inner tubular wall or duct 70 having its top end terminating at the top of the extension 69, and spaced radially inwardly of the extension 69, in concentric relation therewith. The inner duct 70 is integrally connected with four circumferentially equidistantly spaced fresh air elbows 71, having their outer ends rigidly anchored in openings formed in the tubular body portion 67, Figure 8. The elbows serve to rigidly connect the body portion 67 and inner duct 70, in the formation of the integral rigid adapter 66.

Outwardly of the tubular body portion 67, the elbows 71 carry somewhat enlarged horizontal cylindrical extensions 72, integral therewith, and these extensions 72 are arranged directly over the top brace 28 of the main support, as shown.

Four axial flow air circulating fans 73 are provided, and these fans comprise split cylindrical mounting sleeves or wrappers 74 having telescopic engagement over the extensions 72, and resting directly upon the top brace 28 and adjacent leg sections 22, as shown in Figures 2 and 8. The wrappers 74 have opposed radial flanges 75, integral therewith, secured together by bolts 76, so that the sheet metal wrappers 74 are tightly clamped about the extensions 72. A tubular fairing 77 of wood or the like is rigidly mounted

within each wrapper 74, and undercut at one end to form a groove receiving the extension 72, Figure 8. A small permanent magnet motor 78 for each fan is provided, and rigidly mounted centrally within the fairing 77, in spaced relation therewith. An air impeller 79 is carried by the armature shaft of each motor 78 for forcing fresh air axially through the fairing 77 and into the adjacent fresh air elbow 71. The fresh air from the elbows 71 then flows upwardly through the duct 70 and into the heat exchanger to be described. The arrangement is such that the entire weight of the adapter 66, fans 73 and all parts of the heater above the adapter 66 is borne by the top brace 28 and leg sections 22, and none of this weight is transmitted to the generator panels 42, which bear only the weight of the sheet metal flow divider 58 and ring 46.

Each fan motor 78 is driven by a pair of the thermoelectric generator panels 42. The current developed by a pair of the panels is sufficient to operate one of the fan motors at maximum efficiency. Wires 80 and 81 from each fan motor 78 are connected to one endmost copper rod 56 in the top and bottom rows of thermocouples of an adjacent pair of the panels 42, as shown diagrammatically in Figure 16. A wire 82 connects the endmost copper rods 56 of the opposite endmost rows of thermocouples of the panels 42, Figure 16. With this arrangement, all of the 600 thermocouples of the pair of panels 42 are connected in series with the fan motor 78, and the arrangement is repeated for each fan motor in the same manner indicated in Figure 16. The arrangement whereby a pair of the generator panels 42 operates a single fan 73, independently of the other fans is advantageous, because if one or more of the fans should fail to operate, due to a defect in their motor or in the pair of panels 42, the remaining fans will continue to operate for circulating the heated air.

A vertically elongated heat exchanger 83 is mounted upon the adapter 66 and extends above the same for a substantial distance as shown in Figure 1. This heat exchanger 83 comprises inner and outer sheet metal ducts 84 and 85, Figure 9, arranged in concentrically spaced relation and defining a generally annular vertical passage 86 for the rising hot combustion products. The outer duct 85 of the heat exchanger is preferably star-shaped as shown in Figure 9 to provide an increased surface for radiating heat. The inner duct 84 is preferably formed to provide a plurality of circumferentially spaced inner and outer radial extensions or hollow fins 87 and 88, projecting into the bore of the inner duct and into the passage 86, respectively. The extensions 87 and 88 define narrow vertical passages 89 and 90 for the hot combustion products and fresh air respectively. This arrangement provides an increased area for the transfer of heat from the hot combustion products in the passage 86 to the fresh air flowing upwardly through the inner duct 84. The extensions 87 and 88 extend for the entire length of the heat exchanger 83. The heat exchanger 83 is provided at its lower end with inner and outer concentrically spaced cylindrical adapter rings 91 and 92, rigidly secured thereto by welding or the like, and having interfitting telescopic engagement with the cylindrical extensions 70 and 69 of the adapter 66, Figure 8. The heat exchanger 83 is thus bodily mounted upon the adapter 66 and readily removable therefrom. The inner duct 84 is in direct communication with the duct 70, through which the incoming fresh

air from the elbows 71 passes. The passage 86 of the heat exchanger is in communication with the annular passage between the inner duct 70 and body portion 87 of the adapter 66, Figure 9, and the rising hot combustion products must enter the passage 86 and cannot enter the inner heat exchanger duct 84. The rising hot gases in the passage 86 transfer most of their heat to the rising fresh air in the inner duct 84. The star-shaped outer duct 85 will also radiate heat to the surrounding air space to be heated.

An upper adapter and flow divider 93, identical with the adapter 66 but inverted with respect to the same, is carried by the top of the heat exchanger 83. The heat exchanger is provided at its top end with inner and outer concentric cylindrical rings 94 and 95, rigidly secured thereto and these rings engage telescopically with cylindrical extensions 96 and 97 at the lower end of the adapter 93. The adapter 93 has a tubular body portion 98 which communicates with the passage 86 of the heat exchanger and receives the combustion products after the heat exchange process has taken place. Elbows 99 of the adapter 93 receive the heated fresh air from the inner duct 84 of the heat exchanger and these elbows are connected in the adapter 93 in the identical manner that the elbows 71, previously described, are connected in the adapter 66. The four elbows 99 have their discharge ends 100 extending radially beyond the body portion 98 and horizontally disposed for discharging heated air into the surrounding room or space to be heated.

A conical flue section 101 is telescopically mounted upon the top of the adapter 93, as shown, and a cylindrical chimney 102 is telescopically mounted upon the flue section 101 for conveying away the combustion products, after the same have been cooled by the action of the heat exchanger 83.

As previously stated, the adapter 66, fans 73 and all of the parts above the adapter 66 have their weight borne by the top of the main frame, including the brace 28, and the ceramic generator panels 42 do not bear the weight of these parts. The adapter 66, heat exchanger 83 and adapter 93 are readily separable, and may be lifted as a unit from the lower generator and burner unit 20 shown in Figure 3. With this arrangement, it is a very simple matter to remove or replace one or more of the generator panels 42, and to do this, it is merely necessary to remove the locking ring 40 and lift out the particular panel or panels 42 and replace the same by new panels.

Although the operation of the heater is believed to be practically obvious in view of the foregoing description, it may be stated briefly that with the heater assembled as shown in Figures 1 and 2, and a constant level of liquid fuel maintained in the burner 36, the wick 38 is ignited, and burning takes place within the annular combustion space afforded by the refractory lined sleeve 30 and cone 58. A natural updraft of fresh air to support combustion enters the lower end of the sleeve 30 and the hot combustion products pass upwardly and over the stainless steel rods 55. As this occurs, current is developed by the thermoelectric generator panels 42 and the air circulating fans 73 are operated to force fresh air through the inner duct 84 of the heat exchanger 83.

Simultaneously, the hot combustion products flow upwardly through the passage 86 of the heat exchanger and the transfer of heat from the combustion products to the air in the inner duct

84 takes place. The heated air passes outwardly from the upper radial elbows 99 and is directed toward the walls of the room or enclosure. The residual combustion products are discharged through the duct section 101 and chimney 102.

While we have shown and described a simple wick-type burner 36 for the heater, it should be understood that any desired type of updraft burner may be employed.

In Figure 17, we have shown a modified form of thermoelectric generator panel 42', similar to and interchangeable with the panels 42, previously described. In connection with the panel 42', the thermocouples 43' have their hot and cold junctions 53' and 54' embedded in the ceramic material of the panel, as shown, and all of the thermocouple junctions are thus protected from oxidation and other damage which they might be subjected to when projecting outwardly of the sides of the ceramic panels. Each panel 42' is preferably provided near its center and between the hot and cold junctions 53' and 54' with vertical openings or passages 103. Portions of the thermocouple elements, between the hot and cold junctions extend through the passages 103, as shown in Figure 17. If desired, the ends of the passages 103 may be closed, adjacent to the upper and lower ends of the panel 42', and if so closed, the passages 103 are dead air spaced and serve to retard or interrupt the flow of heat from the hot to the cold junctions, and thus aid in increasing the temperature differential between the hot and cold junctions and the efficiency of the thermoelectric generator. If desired, the passages 103 may extend through the top and bottom ends of the panel 42', and air or some other electrically non-conducting fluid may be forced through the passages. This will further tend to interrupt the flow of heat between the hot and cold junctions 53' and 54'. As shown in Figure 17, stainless steel fins or rods 55' are welded to the hot junctions 53' and extend beyond the inner hot side of the panel 42', and copper rods 56' are also welded to the cold junctions 54' and extend beyond the outer or cold side of the panel. In the form of panel shown in Figure 17, the inner ends of the rods 55' and 56' are cast or embedded in the ceramic panel 42', and this provides a very sturdy construction for the thermoelectric generator. Except for the modified arrangement shown in Figure 17 and described above, the panels 42' are identical in construction with the panels 42 previously described, and shown in detail in Figures 13 to 15 inclusive. As previously stated, the panels 42 and 42' are completely interchangeable in the heater assembly shown in Figure 2.

It is to be understood that the forms of the invention herewith shown and described are to be taken as preferred examples of the same, and that various changes in the shape, size and arrangement of parts may be resorted to, without departing from the spirit of the invention or the scope of the subjoined claims.

Having thus described our invention, we claim:

1. In a thermoelectric heater, an upright support including a plurality of circumferentially spaced legs, a substantially horizontal polygonal flange secured to the legs a substantial distance above the bottom of the support and having openings, a plurality of separate upright thermoelectric generator panels having their lower ends resting upon the polygonal flange and having opposed substantially contacting side edges and defining a substantially continuous upright

polygonal wall forming a substantially vertical passage within the support, substantially vertical dowel pins carried by the panels and projecting beyond the upper and lower ends of the same, the lower ends of the dowel pins engaging in the openings of said polygonal flange, a substantially horizontal polygonal locking ring removably mounted upon the upper ends of the panels and provided with openings receiving the upper ends of said dowel pins, the top of the support extending above said locking ring for supporting the weight of heater superstructure above the support, and burner means arranged below said substantially horizontal flange for supplying hot combustion products to the passage defined by said panels.

2. A heater comprising an upright stand, a plurality of separate substantially flat thermoelectric generator panels removably mounted upon the stand in upright edge to edge relation and spaced from the top and bottom of the stand and defining a substantially vertical passage through the stand, a fuel burner carried by the stand below said panels and adapted to supply hot combustion products to said passage, a spreader device carried by the stand and extending into the passage defined by the panels for causing the combustion products to pass near the panels while traveling upwardly through said passage, an adapter arranged above the tops of the panels and having a tubular body portion receiving the upwardly moving combustion products, elbows carried by the adapter and extending radially beyond the tubular body portion and resting upon the top of the stand above said panels and supporting the weight of the adapter, fans connected with the elbows for forcing fresh air into the same and electrically connected with the generator panels, an elongated substantially vertical heat exchanger mounted upon said adapter and having passages receiving the fresh air from the elbows and the hot combustion products from the tubular body portion, and a second adapter mounted upon the top of the heat exchanger and having a tubular body portion receiving the combustion products from the heat exchanger and elbows for receiving heated air from the heat exchanger and directing the same substantially horizontally outwardly from the second adapter.

3. A thermoelectric generator unit comprising an upright stand including circumferentially spaced legs, a substantially horizontal polygonal mounting flange secured to the stand above the lower end of the same, burner means secured to the mounting flange and depending therefrom and disposed within the lower portion of the stand, a plurality of substantially vertical ceramic panels resting upon the horizontal polygonal mounting flange and having substantially vertical meeting edges and arranged to form a substantially continuous upright polygonal wall, the meeting edges of the individual panels being beveled, the polygonal mounting flange having openings near its corners, substantially vertical dowel pins carried by the panels near their meeting edges and extending beyond the upper and lower ends of the panels, the lower ends of the dowel pins engaging in said openings of the polygonal flange, a removable polygonal ring resting upon the tops of the panel and having openings near its corners receiving the tops of the dowel pins, a spreader device resting upon said removable ring and extending into the space defined by said panels and having its lower end spaced above said burner means and causing up-

wardly moving combustion products to pass close to said panels, and thermocouples embedded in the panels, the thermocouples of each panel being electrically connected in series.

5. In a thermoelectric generator unit, a support, a generally vertical thermopile panel mounted upon the support, a plurality of rows of thermocouples having their hot and cold junctions embedded within the panel, the thermocouples in the rows and the rows of thermocouples being connected in series, heat conducting elements secured to the hot junctions of the thermocouples and projecting inwardly of the inner side of the panel, heat conducting elements secured to 10 the cold junctions of the thermocouples and extending outwardly of the outer side of the panel, the panel having generally vertical passages formed therein between said hot and cold junctions, the elements of the thermocouples extending 15 through said passages, the passages serving to retard the flow of heat between the hot and cold junctions of the thermocouples, and burner means carried by the support below said panel and adapted to supply hot combustion products which 20 pass upwardly adjacent to the inner side of the panel.

5. In a thermoelectric heater, an upright support including at least three circumferentially spaced legs, a substantially horizontal polygonal flange secured to the legs a substantial distance 30 above the lower ends of the same, at least three separate upright thermoelectric generator panels having their lower ends resting upon the polygonal flange and having opposed substantially contacting side edges and defining a substantially continuous upright polygonal wall forming a substantially vertical passage within the support, a substantially horizontal polygonal locking ring removably mounted upon the upper ends of the 35 panels and serving to prevent separation of said substantially contacting side edges, the top of the support extending above said locking ring, heat transfer means removably mounted upon the top of the support and having its weight borne by the 40 support so that the generator panels are relieved from excess strain, and burner means arranged below said substantially horizontal flange for supplying hot combustion products to the passage defined by the panels.

6. In a thermoelectric heater, an upright support including at least three circumferentially spaced legs, a substantially horizontal polygonal flange secured to the spaced legs a substantial distance above their lower ends, at least three upright thermoelectric generator panels having their lower ends resting upon the polygonal flange and having opposed substantially contacting side edges defining a substantially continuous upright polygonal wall inwardly of said legs, a substantially horizontal polygonal locking ring removably mounted upon the upper ends of the panels and serving to prevent separation of said substantially contacting side edges, the top of the support extending above the locking ring for a substantial distance to support the weight of heat exchange means above the support, a depending tubular combustion chamber wall arranged inwardly of the legs of the support and having its upper end secured to said substantially horizontal polygonal flange and terminating above the lower end of the support, and burner means dependingly carried by said tubular combustion chamber wall for supplying hot combustion products to the interior of said substantially 60 continuous upright polygonal wall.

7. In a thermoelectric heater, an upright support including at least three circumferentially spaced legs, a substantially horizontal polygonal flange secured to the legs a substantial distance above their lower ends, at least three upright thermoelectric generator panels having their lower ends removably mounted upon said polygonal flange and having their upper ends terminating a substantial distance below the top of the upright support, a substantially horizontal polygonal locking ring removably mounted upon the upper ends of the panels and serving to releasably secure the same together for forming a substantially continuous upright polygonal wall, a spreader device arranged inwardly of the upright panels and spaced therefrom and defining with the panels a substantially annular passage for receiving upwardly flowing hot combustion products, a supporting part carrying the spreader device and resting upon said polygonal locking ring, 10 15 20

burner means dependently secured to the polygonal flange and arranged inwardly of the legs of the support near the lower end of the support, and heat transfer means removably mounted upon the top of the support and having their weight borne entirely by the support so that the panels are free of excessive strain.
